UNITED STATES PATENT OFFICE.

MORRIS ROSENWASSER, OF NEW YORK, N. Y.

LEGGING.

No. 810,962.

Specification of Letters Patent.

Patented Jan. 30, 1906.

Application filed June 26, 1905. Serial No. 207,006.

To all whom it may concern:

Be it known that I, MORRIS ROSENWASSER, residing at 546 and 548 Broadway, New York, in the county of New York and State of New York, have invented certain new and useful Improvements in Leggings, of which the following is a full, clear, and exact description, such as will enable others skilled in the art to which it appertains to make and use the same.

This invention relates to garments, and more particularly to leggings which are especially adapted to be worn by persons affected with rheumatism or by those subject to rheumatic attacks. One of its objects is to provide a legging of such construction as to be easily applied and adjusted upon the leg. Another of its objects is the provision of a legging which will be comfortable to wear and yet of such construction as to provide a warm covering to the part of the leg most susceptible to cold.

Another object is the provision of an adjustable support for the legging.

Other objects will be in part obvious and in part pointed out hereinafter.

The invention accordingly consists in the features of construction, combinations of elements, and arrangement of parts which will be exemplified in the garment hereinafter to be described and the scope of the application of which will be indicated in the following claim.

In the accompanying drawings, wherein is illustrated one of the various possible embodiments of my invention, Figure 1 is a side elevation of the same. Fig. 2 is a side elevation showing the extensible supporting member secured to a garment of the wearer. Fig. 3 is a view of a detail of construction.

Similar reference characters refer to similar parts throughout the several views of the drawings.

Preliminary to a description of the specific features of my invention and in order to render the objects thereof easier of understanding it may be here noted that in leggings, which are usually constructed of substantially thick material, it is essential that they be so constructed as to be easily applied to the leg without a sacrifice of the warmth-giving qualities. In the accomplishment of the above ends I have found it desirable to devise a legging designed to be worn within the shoe and having an entirely-closed portion extending about the ankle to provide a warm covering for that part of the leg, thereby acting as a

preventive against rheumatism, with the further provision of an open upper portion to allow the same to be wrapped about the leg and securely fastened thereto. I have also found it desirable to provide a single adjustable supporting member capable of use as a garter or as a means of direct suspension for the legging from the waistband of other garments or from the corset. The above and other advantages are secured in constructions of the nature of that hereinafter pointed out.

Referring now to the drawings, there is shown at A a legging having a strap or stirrup 1, designed to be worn underneath the shoe and under the hollow of the foot. In order that the material may be prevented from unraveling and that the same may present a substantially smooth surface to the foot, I bind the edges with transversely-extending stitches, as at 2. Openings 3 and 4 extend transversely of the foot part to accommodate the heel and toe, respectively. Above the strap or stirrup 1 is an entirely-closed portion 5, adapted to encircle the ankle, providing a warm covering therefor.

Leg portion 6 is arranged above the ankle portion 5 and is open along its entire extent to allow the same to be wrapped about the leg and fastened, as in the present instance, by buttons 6' and buttonholes 7, although it is obvious that other fastening means, as hooks and eyes, could be used advantageously in this relation. The edges 8 and 9 of leg portion 6 overlap and, if desired, may be bound to give a finished appearance to the garment. To the uppermost button there is attached, by means of a buttonhole 10, an extensible member 11, having in its opposite end a series of buttonholes 12.

While the method of use of my legging should be largely obvious from the above description the same is substantially as follows: The legging being opened is drawn over the foot and pulled up until the closed portion 5 embraces the ankle and the lapped edges buttoned together. The extensible member 11 is then carried around the leg over the upper end of the legging and buttoned at any one of buttonholes 12 to the uppermost button on the leg portion 6. Should it be desired to maintain the legging in position by suspension, extensible member 11 may be buttoned in any of buttonholes 12 to a button on the waistband of other garments or to the corset. The extensible supporting member therefore performs the double office of acting

as a garter or as a supporting device, and by the provision of the series of buttonholes it may be readily adapted to any size of leg or attached to waists or corsets of varying distances from the upper extremity of the legging. Should the number of buttonholes in the upper end of extensible member 11 prove inadequate to properly adjust the same to maintain the legging in the desired position, 10 buttonhole 10, in the lower end thereof, may be applied to a lower one of the buttons in the lapping edge of the legging.

It will accordingly be seen that I have provided a legging which while convenient of 15 adjustment is nevertheless characterized by simplicity and efficiency, the closed portion about the ankle serving to protect that part of the leg and the absence of turned-over portions or seams in the part worn under the 20 foot insuring comfort to the wearer.

As many changes could be made in the above construction and many apparently widely different embodiments of my invention could be made without departing from the scope thereof, I intend that all matter contained in the 25 above description or shown in the accompany-

ing drawings shall be interpreted as illustrative and not in a limiting sense. I desire it also to be understood that the language used in the following claim is intended to cover all 30 of the generic and specific features of the invention herein described and all statements of the scope of the invention which, as a matter of language, might be said to fall there between.

Having described my invention, what I claim as new, and desire to secure by Letters Patent, is—

A legging formed to fit about the limb and ankle of the wearer, having an opening extending from the top portion downwardly and ending at a point substantially above the ankle portion, fastening devices for said opening, and a strap depending from said closed ankle portion and extending beneath the foot 45 of the wearer.

In testimony whereof I affix my signature in the presence of two witnesses.

MORRIS ROSENWASSER.
